UNITED STATES PATENT OFFICE.

WILLIAM B. WHITMORE, OF ORANGE, NEW JERSEY.

SOUND REPRODUCER.

Application filed August 15, 1927. Serial No. 212,944.

This invention relates to a sound reproducer and amplifier, familiarly known as a "loud speaker" and more particularly relates to the vibratory element, commonly called 5 the "diaphragm," which emits sounds in accordance with vibrations applied thereto.

The desideratum is to obtain a true and faithful tonal reproduction of original sounds which have been translated into the 10 vibrations applied to the reproducer so that the reproducer will give a true and clear reproduction not only of notes or sounds of the high, low and intermediate registers, but also will give the blending of tones, the quality, 15 shading, inflection, tempo and peculiar background characteristic, in exact reproduction of the original effort, without omission or addition, except as to volume.

Accordingly, the principal object of the 20 invention is to provide a loud speaker having the above characteristics, and a further object of the invention is to provide a loud speaker of the character described which may serve to amplify the reproduction without 25 lessening the quality thereof.

Another object of the invention is to provide a vibratory element or "diaphragm," which is adapted for use with standard telephonic units to obtain the reproduction and 30 amplification of sounds having the characteristics above mentioned.

Another object of the invention is to provide a loud speaker of the character described, and one which is simple and inexpensive in construction.

Other objects of the invention will be in part obvious and in part pointed out herein-after.

It has been discovered that when a membrane is maintained under tension along lines which converge toward or at a point or apex on the membrane, the quality of the sound reproduction is greatly improved over the quality of sound reproduction that can 45 be obtained from membranes tensioned along divergent lines, as for instance, membranes which are stretched flat across a frame, or membranes which are sufficiently rigid to be self-maintaining in their operating shape. Accordingly, one salient feature of this invention comprises the provision of a membrane which is maintained under a tension acting along lines which converge to or center at a point in the membrane.

55 The membrane itself vibrates in response to vibrations set up by a telephonic unit at-

tached to the membrane, preferably at the point of convergence of the lines of tension or at the point or points of application of force causing the tension.

60 It is an accepted principle in the science of sound that a good conductor of sound waves has a low density as compared to its stiffness. It appears, therefore, that in practically all instances, a good sound conductor 65 is a good sound reproducer, and, therefore, the above cited principle appears to apply to sound reproducers. If now a material of low density and of practically no stiffness is placed under tension to thereby increase its 70 stiffness, without increasing its density, it is found that its sound reproducing properties are improved. It has been known that this advantage has been obtained to some degree when a small area, say about four to five 75 square inches, of material of low density and of low stiffness, is tightly stretched in a flat plane. However, this advantage decreases as the area increases other things being equal, and, therefore, there has heretofore been substantially no success in producing 80 loud speakers employing a large area of material of low density and of low stiffness and increasing the stiffness by stretching in a flat plane.

85 It has been discovered that a relatively large area of material of low density and low stiffness may be placed under tension by forcing some portion of the same out of the flat plane in which it would normally fall if not forced. The forcing of the material out of its flat plane causes the material to be curved toward the point or points of application of force. It has been found by use and experiments that such a curved surface 90 under tension produces a very satisfactory sound reproduction when vibrated. In fact the production thus obtained appears to truly represent the original production without having the extraneous noises usually 95 noted in loud speakers heretofore produced.

100 In defining the contour or curvature which a membrane may take in the construction herein shown, it may be stated that all parts thereof, or substantially all parts of the vibrating surface of the membrane will fall within a surface generated by a straight line having one end at the apex and passing through and following the contour of the periphery of the membrane.

110 There are numerous ways of building a loud speaker in accordance with, and with-

out departing from the scope of this invention. Several possible modifications of the invention will be described hereinafter for the purposes of illustration, reference being had to the accompanying drawings, forming a part of this application, and in which:

Fig. 1 is a front view of a loud speaker embodying the invention in one form;

Fig. 2 is a rear view thereof;

Fig. 3 is a sectional view thereof and is taken on the lines 2—2 of Figs. 1 and 2.

Fig. 4 is an enlarged fragmentary detail taken at the apex of the two tensioned membranes;

Fig. 5 is a front view of a loud speaker illustrating another form in which my invention may be embodied;

Fig. 6 is a sectional view thereof, and is taken on the lines 6—6 of Fig. 5;

Fig. 7 is a fragmentary detail taken at the apex showing an adjustable form of attachment; and

Figs. 8, 9, 10, 11 and 12 are respectively sectional views of several other different forms of loud speakers which embody the invention.

Similar reference characters refer to similar parts throughout the several views of the drawings.

Referring to the drawings the speaker illustrated in Figs. 1, 2, 3 and 4 preferably comprises a frame 20 of suitable material having rigidity. A membrane 21 is secured to one side of this frame by any suitable means, for instance by nails or tacks 22, or with or without a suitable adhesive or other attachment means. On the other side of frame 20, members 23 form a rectangle to which another membrane 24 is secured by any suitable means, for instance by nails or tacks 25, or otherwise. In this preferred form these two membranes are drawn and secured together at the desired points so as to be under tension along lines which converge toward the points when the membranes are attached. Each membrane tensions the other. Any suitable means may be used to cause these membranes to maintain each other under tension. For instance, such means may take the form of a threaded rod 26 which penetrates the two membranes and carries nuts 27 and 28 and washers 29 and 30 between which the membranes are clamped. A telephonic unit 31 is supported on a bracket 32 secured to the frame and is connected with the rod 26 so that the vibrations of the telephonic unit will be applied to both of the membranes simultaneously at the point where they are clamped together.

If desired the telephonic unit may be attached at any desired point so long as the membranes are vibrated in a manner to give satisfactory results. It is to be noted that the membranes become curved and tensioned and that the apex of each is outside of the

general plane in which its periphery is located.

Preferably the membranes 21 and 24 are under tension which keeps them taut, and preferably are also treated with a suitable shrinking compound which may further increase the tension and which gives a more uniform distribution or balancing of strain. Whether it is advisable to apply the shrinking compound depends somewhat on the materials of which the membranes are made. For instance, if fabric is used for the membrane, it is advantageous to apply a sufficient amount of shrinking compound, one form of which is commonly known as airplane dope, to accomplish the desired stiffness. If desired any other suitable compound may be used for this purpose. In the form illustrated in Figs. 1 to 4 inclusive, it is preferred to first attach the smaller membrane to the frame, then join the two membranes together, then affix the second membrane to the frames and then apply the shrinking compound to both membranes.

It will be seen that the desired tensioning of the membranes may be accomplished in one or more of the following ways: tensioning the membranes by stretching when affixing the same to frame 20, by drawing the membranes to each other to a greater or less extent, and by varying the amount and location of the shrinking material or compound. In the application of the latter, it is to be understood that the whole membrane may be covered equally with the shrinking compound and that a portion of the membrane may have one or more additional applications thereby varying the tension in the membrane as a whole and in part.

Preferably the membrane is so shaped and tensioned that the lines of tension converge centrally on the membrane at a pronounced apex thereof, although the membrane may be so shaped that it may be put under sufficient tension without the membrane being distorted to any material extent out of a flat plane.

As illustrated in Figs. 5, 6 and 7 there is shown one means whereby the membrane, such as 33, is maintained under tension and may be adjusted so that the tension may be varied after assembly. Figs. 5, 6 and 7 also illustrate that it is not necessary to provide two membranes, each serving to tension the other, but that the tension means may comprise a resilient member such as 34 which is in no sense a membrane, in that it has no sound emitting characteristics. Membrane 33 is secured to one side of frame 35 and resilient tensioning member 34 is secured to the other side of frame 35. A rod 36 penetrates membrane 33, which is secured to this rod between two nuts 37. The end of rod 36 projects through the strip 34 of resilient material and has a nut 38 threaded upon the

rod whereby the membrane 33 may be drawn more tightly toward strip 34 or may be allowed to recede therefrom to vary the tension under which the membrane 33 is maintained. Rod 36 may be connected with the telephonic unit 39, which is shown supported on a bracket 40 secured to frame 35. If desired, membrane 33 may be secured tightly against strip 34 as in Fig. 6 instead of being adjustable with respect thereto.

Instead of having two mutually tensioning membranes of different sizes, the two membranes may be of the same size. In this event they are preferably connected together to maintain each other under tension by means of a bolt 41, or may be spaced apart as shown in Fig. 8. As shown in this figure, membranes 42 and 43 are secured to opposite sides of frame 44. Membrane 42 is clamped to bolt 41 between two nuts 45. Nut 46 engages membrane 43 so that by adjusting the nut 46 the two membranes may be drawn closer together to increase the tensioning or may be allowed to recede from each other to lessen the tensioning. The vibrations set up in the telephonic unit 47 are transmitted to the bolt 41 to set up corresponding vibrations in the membranes 42 and 43.

It will be understood that the adjustment feature could also be accomplished by having portions of the frames relatively movable in respect to each other in a suitable manner readily apparent to one skilled in the art.

Instead of connecting the two membranes with adjustable tensioning means as heretofore described, these membranes, as shown in Fig. 9 may be connected together by wire or by an equivalent tension member 48. The vibrations from the telephonic unit 49 may be transmitted to the wire 48 through a connection 50 which in this modification is positioned at right angles to the wire 48.

If desired the membranes may be tufted together at a plurality of points, for instance as shown in Fig. 10. In this figure the two membranes 51 and 52 are tufted together by suitable means at 53. The vibrations produced by the telephonic unit 54 are preferably conducted to the membranes at one of the points where the membranes are tufted together. It is to be understood that membranes 51 and 52, however, may be tufted together without actually being in contact in a manner, for instance, as illustrated in Figs. 8 or 9.

If desired three or more membranes of the same or different sizes or shapes may be drawn together at a common point so that each membrane will be maintained under tension by the other membranes connected thereto. Fig. 11 shows an assembly of this type, wherein membranes 55, 56 and 57 are drawn and held together at a central point 58, and thus maintain each other under ten-

sion. The vibrations set up in the telephonic unit 59 may be applied to these three membranes simultaneously by means of a reed 60 which is connected to the membranes at the point 58. A suitable frame 61 is provided to support the membranes at their peripheries.

Instead of drawing two membranes together so that each will hold the other under tension, the membranes may maintain each other under tension by being held apart, such for instance as by a rigid post. For example, in Fig. 12 the membranes 62 and 63 are clamped by means of nuts 64 and 65 respectively to a bolt or rod 66 which spaces the membranes so far apart from each other that they are under the desired tension. These membranes are secured at their peripheries to a suitable frame 67.

From the above it will be apparent that in accordance with this invention the loud speaker may comprise one, two or more membranes, each capable of emitting and reproducing sounds in accordance with vibrations applied thereto, as by a telephonic unit of standard construction. The periphery of any membrane may be circular, square or otherwise as desired. When the speaker includes more than one membrane, the membranes may be of the same size or may be of different sizes. It may be that a membrane of small size is best to reproduce notes and sounds of a high register and that membranes of large area are best adapted to reproduce sounds and notes of a low register. This invention permits the association together in a single loud speaker of membranes having different areas, different shapes and different tensions whereby the speaker is perfectly adapted to notes and sounds of high and low register and intermediate register. At the same time, as before stated, each membrane may be maintained under tension by another membrane or membranes associated therewith, or by independent tensioning means, and all the membranes vibrate to translate into sound the vibrations applied thereto by the telephonic unit, each membrane serving in accordance with its size and other characteristics.

As aforesaid, any suitable means may be provided for placing any membrane under tension along lines which converge inward of its periphery, so long as such means do not interfere with the proper vibration of the membrane. Accordingly the membrane may be tensioned and anchored inward of its periphery to any resilient means which permits vibration of the membrane.

Another form for carrying out the purpose of tensioning the membranes may be stated as follows: The periphery of a membrane is fastened to a suitable frame and the center of the membrane extended until the

material of the membrane becomes tensioned. While the membrane is under this tension a coating of only slightly compressible substance is applied. The tension on the membrane may be thereafter released but the membrane will not completely go back to its original position due to the presence of the coating substance which opposes and balances to an extent the contractual effort of the membrane. The membrane material, therefore, remains tensioned to some extent after the external tension has been released, but it does not have the stiffness desired for the reproduction as described herein. It may also be understood instead of applying a coating substance as noted that any suitable material or sustaining frame may be associated with the membrane after it has been tensioned thereby maintaining the membrane under tension after the release of the original tension so that it will vibrate in response to means acting on the membrane for vibrating the same.

It is usually immaterial on which side of any membrane the telephonic unit is placed, and if there are two mutually tensioned membranes, the telephonic unit may be placed on either side of them or between them in a desired position.

30 The membranes when vibrating cooperate and may be considered as a unit vibrating element or diaphragm.

Any suitable material may be used for any of the membranes, and it is to be understood that there is no restriction to any particular substance. Suitable substances for this purpose may be linen, muslin, cloth, skin, leather, and natural or artificial membranes, such as cellulose xanthate. It is to be understood that one membrane may be made of one material, and another membrane made of another material.

When referring to cloth membrane, for instance, it is to be understood that the membrane material may be of ordinary fabric which is preferably closely woven. Also, when the cloth, or fabric of that nature, is employed ready for use the pores thereof are substantially filled by the coating herein mentioned.

It is not essential to follow any precise order of placing the membranes in position and causing them to be tensioned. For instance, it is immaterial whether the shrinking compound, if used, be applied to the membrane before or after the membrane is attached in place. If there are two membranes they may be first attached to the frames, then drawn together, and then treated with a shrinking substance; or they may be first attached together, then secured to the frame, and then treated with the shrinking substance; or first one membrane may be secured to the frame, with or without having the shrinking substance

applied thereto, then the other membrane may be attached to the first one, and then to the frame, and then the shrinking substance applied to the second membrane.

As many changes can be made in the above construction and as many different embodiments of this invention can be made without departing from the scope thereof, it is intended that all matter contained in the above description so shown in the accompanying drawings be interpreted as illustrated and not in a limiting sense.

What is claimed is:

1. A sound reproducer of the character described, comprising, in combination, a supporting frame, a vibratory membrane fastened to said frame, resilient means maintaining said membrane under tension along lines converging inward of its periphery and toward a point located outside of the general plane of the periphery, said membrane as so tensioned having substantially all parts thereof within a surface generated by a straight line having one end at said point and passing through and following the contour of the periphery of the membrane, and means for applying sound reproducing vibrations to said membrane.

2. A sound reproducer of the character described, comprising, in combination, a supporting frame, a vibratory membrane fastened to said frame, resilient means maintaining said membrane under tension along lines converging inward of its periphery and toward a point located outside of the general plane of the periphery, said membrane as so tensioned having substantially all parts thereof within a surface generated by a straight line having one end at said point and passing through and following the contour of the periphery of the membrane, and means for applying sound reproducing vibrations to said membrane, said resilient means including a vibratory member to which said membrane is connected.

3. A sound reproducer of the character described, comprising, in combination, a supporting frame, a vibratory membrane fastened to said frame, resilient means maintaining said membrane under tension along lines converging inward of its periphery and toward a point located outside of the general plane of the periphery, said membrane as so tensioned having substantially all parts thereof within a surface generated by a straight line having one end at said point and passing through and following the contour of the periphery of the membrane, and means for applying sound reproducing vibrations to said membrane, said resilient means including a second vibratory membrane joined to the first membrane.

4. A sound reproducer of the character

- described, comprising, in combination, a supporting frame, a vibratory membrane fastened to said frame, resilient means maintaining said membrane under tension 5 along lines converging inward of its periphery and toward a point located outside of the general plane of the periphery, said membrane as so tensioned having substantially all parts thereof within a surface 10 generated by a straight line having one end at said point and passing through and following the contour of the periphery of the membrane, and means for applying sound reproducing vibrations to said membrane, 15 said resilient means including a second vibratory membrane, said membranes being connected to each other substantially at their centers.
5. A sound reproducer of the character described, comprising, in combination, a supporting frame, a vibratory membrane fastened to said frame, resilient means maintaining said membrane under tension along lines converging inward of its periphery 20 and toward a point located outside of the general plane of the periphery, said membrane as so tensioned having substantially all parts thereof within a surface generated by a straight line having one end at said 25 point and passing through and following the contour of the periphery of the membrane, and means for applying sound reproducing vibrations to said membrane, said resilient means including a second vibratory membrane, said membranes being tensioned toward each other.
6. A sound reproducer of the character described, comprising, in combination, a supporting frame, a vibratory membrane fastened to said frame, resilient means maintaining said membrane under tension along lines converging inward of its periphery and toward a point located outside of the general plane of the periphery, said membrane as so tensioned having substantially all parts thereof within a surface generated by a straight line having one end at said point and passing through and following the contour of the periphery of the membrane, and means for applying sound reproducing vibrations to said membrane, said resilient means including a second vibratory membrane joined to said first membrane, said membranes being of different sizes.
7. A sound reproducer of the character described, comprising, in combination, a supporting frame, a vibratory membrane fastened to said frame, resilient means maintaining said membrane under tension along lines converging inward of its periphery and toward a point located outside of the general plane of the periphery, said membrane as so tensioned having substantially all parts thereof within a surface generated by a straight line having one end at said
- point and passing through and following the contour of the periphery of the membrane, and means for applying sound reproducing vibrations to said membrane, said resilient means including a second vibratory membrane joined to said first membrane, said membranes being of different sizes and being connected together at their centers. 70
8. A sound reproducer of the character described, comprising, in combination, a supporting frame, a vibratory membrane mounted in association with said frame, resilient means maintaining said membrane under tension along lines converging inward of its periphery and toward a point located outside of the general plane of the periphery, said membrane as so tensioned having substantially all parts thereof within a surface generated by a straight line having one end at said point and passing through and following the contour of the periphery of the membrane, and means for applying sound reproducing vibrations to said membrane, said resilient means being adjustable whereby the tension on the membrane may 80 be varied. 85
9. A sound reproducer of the character described, comprising, in combination, a supporting frame, a vibratory membrane fastened to said frame, resilient means maintaining said membrane under tension along lines converging inward of its periphery and toward a point located outside of the general plane of the periphery, said membrane as so tensioned having substantially all parts thereof within a surface generated by a straight line having one end at said point and passing through and following the contour of the periphery of the membrane, and means for applying sound reproducing vibrations to said membrane, 90 said resilient means including a second vibratory membrane, said membranes being connected together by an adjustable device whereby the tension force of the membranes on each other may be varied. 95
10. A sound reproducer of the character described, comprising, in combination, two oppositely disposed substantially vertical supporting frames connected together, two coated cloth membranes fastened one to each of said frames and drawn together to create tension in each and connected together as so tensioned, and means for applying sound reproducing vibrations to said membranes. 105 110
11. A sound reproducer of the character described, comprising, in combination, two oppositely disposed substantially vertical supporting frames connected together, two coated cloth membranes fastened at their edges, one to each of said frames, and drawn together to create tension in each and as so tensioned connected together at their central points, and means for applying sound reproducing vibrations to said membranes. 120 125 130

12. A sound reproducer of the character described, comprising, in combination, two oppositely disposed substantially vertical supporting frames connected together, two ⁵ coated cloth membranes fastened at their edges, one to each of said frames, and drawn together to create tension in each and as so tensioned connected together at their central points, means for applying sound ¹⁰ vibrations to said membranes, and means for adjusting the tension in said membranes after they have been joined.

13. In a loud speaker, in combination, an open rectangular supporting frame, a cloth ¹⁵ membrane fastened to said frame on one side thereof, a second frame supported by said first frame in proximity to the other side of said first frame, a second cloth membrane of relatively smaller size than the first ²⁰ membrane mounted on said second frame, said membranes being joined together at their centers by materially drawing said larger membrane out of a plane passing through its periphery thereby placing both ²⁵ of said membranes under tension, said membranes having their stiffness increased by

application of a shrinking material, said membranes being thereby balanced against each other and each being under tension, and means for applying sound reproducing vibrations to said membranes while under said balanced tension. ³⁰

14. In a loud speaker, in combination, an open rectangular supporting frame, a cloth membrane fastened to said frame on one ³⁵ side thereof, a second frame supported by said first frame in proximity to the other side of said first frame, a second membrane fastened to said second frame, said membranes being placed under tension and so held by opposing one point in one membrane against a point in the other membrane thereby distorting each point out of the periphery of its membrane so that each membrane will take a position which falls within a surface ⁴⁰ generated by a straight line having one end at its said point and passing through and following the contour of its periphery, and means for applying sound reproducing vibrations to said membranes. ⁴⁵ ⁵⁰

WILLIAM B. WHITMORE.
